UNITED STATES PATENT OFFICE.

CHARLES R. MABEE, OF TOLEDO, OHIO.

CENTRIFUGAL DRIER.

1,420,650.

Specification of Letters Patent. Patented June 27, 1922.

Application filed December 15, 1913, Serial No. 806,891. Renewed March 1, 1919. Serial No. 280,144.

To all whom it may concern:

Be it known that I, CHARLES R. MABEE, a citizen of the United States, residing in the city of Toledo, county of Lucas, and State of Ohio, have invented certain new and useful Improvements in Centrifugal Driers; and I do declare that the following is a full, clear, and exact description of the same.

This invention relates to centrifugal driers, and especially to that class of driers which are employed for the drying of brewers' slops, wet grain, and other similar products. It provides means for the application of centrifugal force and circumferential motion around and against the concave cylindrical walls of a heated container and means for the withdrawal of the dried contents of the container when the process is completed.

To enable others skilled in the art to which it appertains to make and use the same, I will proceed to describe the invention with reference to the drawing, in which similar reference characters refer to similar parts in all the figures.

Figure 1 is a vertical section of my improved drier and separator, Figure 2 is an end elevation of the same, Figure 3 is an elevation of the opposite end from that shown in Figure 2 and Figure 4 is a detail perspective view of the interior rotatable frame.

Referring more particularly to the drawings, 1 designates the container, which is essentially a horizontally disposed cylinder, provided with an external steam jacket 17, 35 provided with an inlet 18 for the introduction of steam and an outlet 19 for the removal of the water of condensation. The internal rotating parts comprise a plurality of metallic rings 20, rigidly secured in parallel alignment by a plurality of angle irons 5 spaced apart about the periphery of said rings and rigidly attached to the extremities of fan blades 4. A shaft 2 passes centrally through the rings and the central point of 45 the fan blades to which it is keyed, said shaft being journaled in the cylinder heads 10 and 11 and adapted to turn in the longitudinal axis of the container. A motor 6 mounted on a bracket 23 attached to the cylinder head 10, is disposed in the cylindrical axis of the container and is connected to the shaft 2, giving the necessary rotary motion 50 to said shaft. An inlet pipe 24 removably

attached to the aperture 12 in the cylinder head 10 affords means for the introduction 55 to the container of the materials to be treated. A screened aperture 13 in said cylinder head and a similar screened aperture 14 in the opposite head affords means for the introduction of air into and the escape of 60 moist and heated air from the respective cylinder heads of said container. A door 27 in the cylinder head 11, swings outwardly when the container is given a downward angular displacement about the fulcrum 16, 65 by means of lever 26 fulcrumed at 8 and adapted to maintain the container normally in a horizontal position. One or more trippers 21, disposed longitudinally of the interior surface of the container, are employed, the same preferably extending substantially from end to end of the cylinder and adapted to impart to the moving layer 70 of material a riffle action. The trippers 21 project inwardly from the treating surface 75 of the container a very slight distance with the result that the agitation of the material will be comparatively slight, so that the continuous movement of the layer is not substantially interrupted, while at the same 80 time that portion of the film in contact with the heating surface, will be continually changing.

The operation of my improved centrifugal drier is as follows:

The material to be treated is introduced within the container 1, by means of pipe 24 and the aperture 12 in the head 10 of the container, the rotatable frame 4 having been previously set in motion by the motor 6 and the container having been heated to the desired temperature by the admission of steam to the jacket 17.

A plurality of conveyor arms 5 in moving contact with the material introduced, communicate to said material a motion circumferentially of the container and cause said material to assume the form of a moving thin layer pressing outwardly against the concave surface of said container, said contents through the medium of said pressure, absorbing heat more rapidly and in greater amount than would be the case in the absence of said motion and said outward pressure. The material operated upon moving necessarily at a high rate of speed in order to

maintain said thin layer, cause the vapor of evaporation to separate rapidly from the thin layer and to pass through the central portion of the container as a result of the motion 5 imparted to it by the fan blades, in the direction of the vapor outlet 14. As the layer passes over the tripper or trippers 21, that portion of the product operated upon pressing outwardly on the heating surface, is continually changing, and, owing to the fact 10 that the portion of the material first dried is lighter and passes to the inside of the film of material, while the moist or heavier portion of said material is forced outwardly 15 against the heated surface, the drying process is greatly accelerated.

When the treatment has been completed, one end of the container is lowered by releasing lever 26 and giving a partial turning movement to the arm 9, pivotally supported at 8, the container being tilted on the bearing 16. In addition to the action of the fan blades 4 in supporting the arms 5, they circulate air within the container and when 25 the door 27 inclines outwardly as a result of lowering the corresponding end of said container, said fan blades or supports drive the finished product down the inclined concave surface and out of said container. 30 In this invention, heat may be applied to the container by hot gases, electricity or other suitable means.

While the construction set out is excellently adapted for the employment of my invention in practice, I do not limit myself to the details, as they may be modified without departing from the spirit of the invention.

Certain features herein described and 40 illustrated are made the subject matter of separate applications for patents, and are not claimed herein. For instance in my application, Serial No. 77,996, filed February 12, 1916, being in part a continuation of my 45 application, Serial No. 718,114 filed August 31, 1912, I have illustrated, described and claimed broadly the method of treating liquid substances or substances containing liquid by subjecting a circular layer of material 50 under pressure to movement circumferentially and lengthwise over a treating surface while permitting the vapors to escape, said treatment being carried out either at or below atmospheric pressure, and I therefore 55 reserve the right to claim all matters not embraced by the claims, and herein described, in separate applications.

While I have above mentioned brewers' 60 slop as one of the fluid materials which can be treated in the present mechanism, and have also referred to wet grain, it will be understood, that it was not intended to thereby restrict the matters of novelty in structure or operation to any specific material requiring rapid and economical withdrawal of

water and heretofore, in one branch of art or another, treated for that purpose. The slop and wet grain were mentioned as typical of numerous materials which can be treated to advantage in the mechanism herein presented in eliminating the water component, if they are susceptible of being disposed in a layer on the container wall by rotary devices such as indicated at 20 and 5, and arranged to permit the vaporized water to be forced out from the container by internally disposed devices substantially similar to those at 4. In my co-pending applications Nos. 718,114, filed August 31, 1912; 738,178, filed December 23, 1912; 797,087 (renewed as 108,956), filed October 24, 1913, 805,598, filed December 9, 1913; 806,888, filed December 15, 1913 (renewed as 358,433); 806,889, filed December 15, 1913 (renewed as 366,962), filed December 15, 1913; 806,890, filed December 15, 1913 (renewed as 280,143; 40757, filed July 19, 1915; 77,996, filed February 12, 1916; 277,904, filed February 18, 1919, respectively. I have shown mechanisms and described methods which, respectively, have one or more features that are also incident to the subject matter herein; for example, in several of the said application records is presented the forming of a layer of the material to be treated, which layer is circular in cross-section and moves circumferentially and lengthwise of the container, the mechanisms referred to permitting or causing the vapor and air to freely and rapidly escape 100 axially from the interior of the container. In some of said records the expelling of the vapors and gases is described as being caused by external devices, positioned, respectively, at one suitable place or another 105 either at the end of the evaporating chamber or at other points outside thereof.

And I reserve the right to claim, in the said other applications the novel subjects matter therein disclosed, and not herein claimed.

Having thus fully described my invention, what I claim is—

1. In a centrifugal drier, a horizontally disposed cylindrical container, means for applying heat externally thereto and means for applying a centrifugal and circumferential motion to the contents thereof, whereby a moving layer of material is formed on the wall of the container, and means within the container for expelling the vapors from the space within the layer of material.

2. In a centrifugal drier, a horizontally disposed cylindrical container, a steam jacket surrounding the peripheral wall of the container, means for applying a centrifugal and circumferential motion to the contents thereof whereby a moving layer of material is formed on the wall of the container, said container having an inlet for the mate-

rial at one end, and an outlet for the material adjacent its opposite end, and said container having an auxiliary opening in each end, and means within the container for positively expelling the vapors through one of said auxiliary openings from the space within the layer of material.

3. In a centrifugal drier, a horizontal cylindrical container, external means for heating said container and a rotatable frame axially mounted within said container adapted to apply centrifugal motion to the contents thereof and means for driving said frame circumferentially of the interior of said container at a high rate of speed whereby there is maintained on the wall of the container a moving layer of material, and internal means for removing the vapor of evaporation.

20 4. In a centrifugal drier, an externally heated and horizontally disposed cylindrical container, a shaft mounted axially thereof, a plurality of fan blades mounted on said shaft, arms parallel to the shaft mounted on the fan blades, a plurality of rings concentric with the shaft mounted on the arms and means for applying rotary motion to the shaft.

5. In a centrifugal drier, an externally heated, horizontal cylindrical container, a shaft mounted axially thereof, a plurality of fan blades rigidly mounted on said shaft, arms parallel to the shaft rigidly attached to the adjacent ends of the several fan blades, 35 a plurality of rings concentric with the shaft, spaced apart and rigidly attached to said arms, other arms spaced apart attached to said rings and means for applying rotary motion to said shaft.

40 6. In a centrifugal drier, an externally heated horizontal cylindrical container, cylinder heads at the opposite ends thereof, one of said heads having a large discharge opening for the escape of vapors, bearings centrally of said heads, a shaft mounted in said bearings, a motor mounted on the shaft externally of the container, means for introducing materials to be treated within said container, means for withdrawing the same 45 therefrom, means for imparting to said materials a rotary centrifugal motion against the heated walls of the container, and means mounted on said shaft for rapidly expelling the vapors through said 55 large opening.

7. In a centrifugal drier, an externally heated horizontally disposed cylindrical container, said container having an inlet at one end and a normally closed outlet at its 60 opposite end, rotatable means within the container for applying a centrifugal and circumferential motion to the contents thereof whereby a moving layer of material is formed on the wall of the container, means 65 for lowering the outlet end of the container,

and means permitting discharge of material through said outlet when the end of the container is lowered.

8. In a centrifugal drier, an externally heated horizontal cylindrical container, a cylinder head at one extremity thereof provided with an aperture for the reception of material to be treated, a cylinder head at the opposite extremity of said container provided with a semi-circular screened aperture concentric with the head and a segmental door hingedly attached to said head, a shaft mounted in said container, a motor attached to said shaft, and conveying means on the shaft within the container, horizontal 77 arms mounted on the supports adapted to move in close proximity to the concave surface of the container.

9. In a centrifugal drier, an externally heated and horizontally-disposed cylindrical 85 container having means therein for applying and maintaining under movement a layer of material on the inner surface of the container, a support fulcrumed externally to one end of the outer surface of the container, a raising and lowering lever similarly disposed at the opposite end thereof, to raise and lower one end of said container, and means for the removal of the contents thereof. 90

10. In an apparatus for treating material to change the condition or consistency thereof, the combination of a cylindrical container, means for applying to the wall of the container a temperature different from that of the material being treated, a rotatable shaft extending longitudinally of the container, separated conveyor members extending longitudinally of and adjacent the inner surface of the wall of the container, 100 and supports between the conveyor members and shaft, said supports taking the form of fan blades.

11. In an apparatus for treating material to change the condition or consistency thereof, the combination of a horizontally disposed cylindrical container, external means for applying to the wall of the container a temperature different from that of the material to be treated, a horizontally disposed 110 rotatable shaft within the container, separated conveyor members extending longitudinally of and adjacent the inner surface of the wall of the container, supports between the conveyor members, and shaft, said supports taking the form of fan blades, annular ring members connecting the conveyor members, and means for rotating the shaft.

12. In an apparatus for treating material to change the condition or consistency thereof, the combination of a cylindrical container having end walls with openings therein, means for applying to the peripheral wall of the container a temperature different from that of the material being 125 130

- 2
treated, means within the container for forming and maintaining under movement a circular layer of material on the interior surface of the container, and a screen in 5 said end wall-openings.
13. In an apparatus for treating material to change the condition or consistency thereof, the combination of a horizontally disposed cylindrical container, means for 10 applying to the wall thereof a temperature different from that of the material to be treated, means within the container for forming and maintaining under movement a circular layer of material on the inner surface 15 of the wall of the container, end walls for the container, one of said end walls having an inlet opening for the material to be treated, and a screened opening, and the opposite wall having a screened opening.
14. In an apparatus for treating material to change the condition or consistency thereof, the combination of a horizontally disposed cylindrical container, means for 20 applying to the wall thereof a temperature different from that of the material being treated, conveyor members within the container extending longitudinally thereof adjacent the interior surface, and mounted for rotation, said cylinder being mounted for 25 tilting movement and having an outlet adjacent the rear end thereof whereby to permit the material to flow out of the cylinder.
15. In an apparatus for treating material to change the condition or consistency 30 thereof, the combination of a horizontally disposed cylindrical container, means for applying to the wall thereof a temperature different from that of the material being treated, the container having an outlet adjacent the rear end thereof, a movable 35 closure for the outlet, conveyor means within the container adapted to move a layer of material over the surface of the container, and means for lowering the outlet end of 40 the container to permit the material to flow out of said outlet.
16. In an apparatus for treating material to change the condition or consistency 45 thereof, the combination of a horizontally disposed cylindrical container, means for applying to the wall thereof a temperature different from that of the material being treated, the container having an outlet adjacent the rear end thereof, a movable 50 closure for the outlet, conveyor means within the container adapted to move a layer of material over the surface of the container, and means for lowering the outlet end of 55 the container to permit the material to flow out of said outlet, said closure automatically 60 opening upon the lowering movement of the container.
17. In an apparatus for treating material to change the condition or consistency thereof, the combination of a cylindrical con- 65 tainer, means for applying to the wall thereof a temperature different from that of the material being treated, conveyor means extending longitudinally of the container adjacent the interior surface thereof, for forming and maintaining a moving layer 70 of material over said surface, and a fan moving in the space within the layer of material for expelling vapors.
18. In an apparatus for treating material to change the condition or consistency thereof, the combination of a horizontal cylindrical container, means for applying to the wall thereof a temperature different from that of the material being treated, 75 means within the container for forming and maintaining under movement a layer of the material on said surface, and a longitudinally extending projection or projections on the interior surface of the container, and 80 said container having a relatively large end wall opening for the rapid discharge of vapors from the zone formed by said moving layer of material.
19. In an apparatus for treating material to change the condition or consistency thereof, the combination of a cylindrical container, means for applying to the wall thereof a temperature different from that of the material being treated, means for 85 applying a centrifugal and circumferential motion to the contents of the container, and internal means for removing the vapor of evaporation.
20. In a centrifugal drier an externally heated horizontal cylindrical container, a cylinder head at one extremity thereof, a cylinder head at the opposite extremity of 90 said container provided with a door hingedly attached to said head and a vapor escape opening, a shaft mounted in said container, a motor attached to said shaft, radial supports on the shaft internally of the container, said supports taking the form of fan blades, and horizontal arms mounted on the 95 supports adapted to move in close proximity to the concave surface of the container.
21. The method of treating material to change the condition or consistency thereof, which consists in forming and maintaining 100 under continuous movement a circular layer of material in contact with a cylindrical treating surface, having a temperature different from that of the material being treated, subjecting said moving layer of 105 material to a riffle action, maintaining a central quiet zone, and maintaining a copious discharge for the vapors from said central quiet zone.
22. In an apparatus for treating material to change the condition or consistency thereof, the combination of a cylindrical container, means for applying to the wall of the container a temperature different 110 from that of the material being treated, a 115

shaft extending longitudinally of the container, separated conveyor members extending longitudinally of and adjacent the inner surface of the wall of the container, means for rotating the shaft at a high speed whereby to apply the material in circumferential layer formation in contact with the inner surface of the container and for moving the layer of material over said surface, said container having an inlet for the material adjacent one end and an outlet adjacent the opposite end, and an auxiliary

outlet for the free escape of vapors, and blower means arranged at a point within said conveyor members to expel the vapors through said auxiliary outlet. 15

In testimony whereof, I have hereunto signed my name, this 24th day of November, 1913, in the presence of two subscribing witnesses.

CHARLES R. MABEE.
